THOMAS S. GILMORE,
INVENTOR.

R. C. Wright

ATTORNEY.

UNITED STATES PATENT OFFICE.

THOMAS S. GILMORE, OF LA GRANDE, OREGON.

PNEUMATIC SANDER.

Application filed January 13, 1926. Serial No. 81,015.

My invention relates to traction sanders as a class.

The object of my invention is to provide a device of this class, which has an apparatus for pneumatically loosening and forcing sand from a reservoir toward a pre-determined location and is particularly intended for locomotives and vehicles which are run upon rails, but may be adapted to other vehicles requiring traction aid. I attain these objects, as well as other advantages, by the construction, combination, and arrangement of parts illustrated in the accompanying drawings which form a part hereof.

Fig. I is a side elevation of the device, partly in section.

Fig. II is a longitudinal, sectional view of the nozzle on the line II-II in Fig. III.

Fig. III is a view of the larger end of the nozzle.

Like characters refer to like parts in the views.

The pipe 1 extends from a source of sand supply, such as a sand box upon a locomotive. The opposing end of this pipe is connected with the upper opening 2 of a sand trap 3 by threaded joints. A pipe 4 extends from a source of air supply under pressure to and into a valve shell 5, in which is a three-way valve of common type having an operating lever 6. From the valve shell a pipe 7 extends from a port 8 in the shell to a connection member 9, which has a conical shaped passage 10, the smaller opening at the connection with said pipe, the larger opening being within a lateral port 11 of the trap 3 which port is below and at one side of the inlet 2. In the larger passage end of the member 9 a threaded nozzle 12 is positioned. The nozzle has a discharge opening 13 on its end, of a pre-determined diameter. About the base of the nozzle and within the port 11 is a series of small discharge orifices 14, aligned vertically on each side of the nozzle center, the number and diameter of the same are also pre-determined. Opposite the end of the nozzle 12 is another lateral port 15 in the trap 3 positioned below and at one side of the inlet 2. A pipe 16, having threaded connections, extends from within this port outwardly to a position where sand may be forced through the pipe to deposit along a desired location, as, for example, upon a rail in advance of a wheel travelling forwardly thereon. From the valve shell an-

other pipe 17 extends from a port 18 in the shell to a nozzle 19 of like kind positioned in a port 20 of the trap 3. Opposite the latter nozzle 19 is a port 21 in the trap 3. A pipe 22, having threaded connections, extends from this port outwardly to a position where sand may be forced through the pipe to deposit along a desired location as, for example, upon a rail in advance of a wheel travelling rearwardly thereon. The lever 6 is shown in the position assumed to open the valve for discharge of air through the port 8 with the discharge port 18 closed. When the lever is in the dotted line position 6^a the said ports are closed and opened reversely. When the lever is in dotted line position 6^b both ports are closed. Sand is discharged by gravity through the pipe 1 into the trap 3.

It will now be seen that the valve being closed to the air supply pipe 4, the trap is filled with sand by gravity discharge thereof through the pipe 1. Upon moving the lever 6 to the position shown in Fig. I, air under pressure rushes through the port 8 and the nozzle 12 into the trap chamber. The nozzle end being in direct alignment with the port 15, sand is driven through it and through the pipe 16 upon a rail in advance of a locomotive driving wheel for example. The air at the same time rushes through the adjacent openings 14, vertically aligned on each side of the nozzle, and breaks up any packed sand and tends to keep the sand mass sufficiently loosened and drive it toward the discharge port so as to allow the air blast from the nozzle end to drive the loose sand into the pipe 16. The nozzle of the pipe 17, not being operated, the sand is carried as it falls from the pipe 1 by the strong air current into the pipe 16. When the nozzle 12 is not operated the sand falls below it in the trap, and upon operating the nozzle of the pipe 17 a like action follows to a discharge of sand through the pipe 22 as already described. It has been found in the operation of locomotive sanders that the sand often becomes wet or hardened into a mass or lumps which clog the discharge pipes or trap and thus prevent the flow upon the rail. It has also been found that apparatus of various kinds intended to force the sand out of a trap and pipes have not overcome these difficulties. The absolute need and demand for a sander instantly efficient at critical moments in the movement

of locomotives, for instance, is so apparent that argument in support is unnecessary. The arrangement of my device with its trap, filled by gravity, and the directly aligned 5 pneumatic air current through the trap under considerable pressure toward the discharge pipe, together with the auxiliary pneumatic side air current, as well as other features, overcomes these difficulties. My 10 device has been tested in operation and proven to be entirely efficient in these matters and is new and useful. It is also very economical in cost of manufacture and installation as part of the equipment in any 15 common type locomotive and can be placed at very reasonable cost in any other vehicle requiring it. The device as shown has apparatus for a two-way discharge outwardly of the sand. A single discharge may be 20 arranged if desired by omitting the duplicated parts. The position of the openings 14 is such as to afford a discharge of air throughout the body of sand in the trap and toward the port 15. The end of the nozzle 25 12 is positioned at the beginning of the port 15 to allow discharge of air at a point where a suction will occur to draw sand from above and force it through the port.

I claim:

30 1. In a sanding device the combination of; a trap having a vertical inlet adapted for the passage of sand through it into the trap, the latter also having an air intake port 11 and a discharge port 15, positioned laterally in alignment in opposite walls of the trap, below its inlet, and a nozzle having 35 its base secured in the port 11, its free end being approximately at the entrance of the port 15 within the trap, said nozzle being also provided with orifices in its base positioned vertically on each side of the nozzle center, supplying thereby auxiliary openings from the port 11 directly into the trap.

40 2. In a sanding device having a trap adapted to receive sand therein and an air intake port 11 and a discharge port 15 aligned in the opposing trap walls laterally below the inlet, a nozzle having its base secured in the port 11, its free end being approximately at the entrance of the port 45 15 within the trap, said nozzle also having orifices in its base positioned vertically on each side of the nozzle center, supplying thereby auxiliary openings from the port 11 directly into the trap.

50 3. In a sanding device the combination of; a trap having a vertical inlet adapted for the passage of sand through it into the trap, the latter also having an air intake port 11 and a discharge port 15 positioned laterally in alignment in opposing walls of the trap, below its inlet, a first pipe extending 55 from a source of air supply under pressure to a connection for discharge through the port 11, a control valve in said pipe, and

a nozzle having its base secured in the port 11, its free end being approximately at the entrance of the port 15 within the trap, said nozzle being also provided with orifices in its base positioned vertically on each side 70 of the nozzle center, supplying thereby auxiliary openings from the port 11 directly into the trap.

4. In a sanding device the combination of; a trap having a vertical inlet adapted for the passage of sand through it into the trap, the latter also having an air intake port 11 and a discharge port 15 positioned laterally in alignment in opposing walls of the trap, below its inlet, a first pipe extending from 75 a source of air supply under pressure to a connection for discharge through the port 11, a control valve in said pipe, a nozzle having its base secured in the port 11, its free end being approximately at the entrance of the port 15 within the trap, said nozzle being also provided with orifices in its base positioned vertically on each side 80 of the nozzle center, supplying thereby auxiliary openings from the port 11 directly into the trap, and a second pipe extending from a source of sand supply to a connection for discharge through the trap inlet.

5. In a sanding device the combination of; a trap having a vertical inlet adapted for the passage of sand through it into the trap, the latter also having an air intake port 11 and a discharge port 15 positioned laterally in alignment in opposing walls of the trap, below its inlet, a first pipe extending from 95 a source of air supply under pressure to a connection for discharge through the port 11, a control valve in said pipe, a nozzle having its base secured in the port 11, its free end being approximately at the entrance of the port 15 within the trap, said nozzle being also provided with orifices in its base positioned vertically on each side 100 of the nozzle center, supplying thereby auxiliary openings from the port 11 directly into the trap, and a second pipe extending from a source of sand supply to a connection for discharge through the trap inlet, and a third pipe extending from a receiving connection 105 in the port 15 to a place of sand discharge.

6. In a sanding device the combination of; a trap having a vertical inlet adapted for the passage of sand through it into the trap, the latter also having an air intake port 11 and a discharge port 15, positioned laterally in alignment in opposite walls of the trap, below its inlet, a member having a conical opening through it, the end having the cone base therein secured within the 110 port 11, the opposing end being adapted to engage a pipe to receive therefrom air under pressure and allow its passage through the member, and a nozzle having its base secured in the discharge end of said 115 member, extending therefrom with its free 120 end.

end approximately positioned at the entrance of the port 15 within the trap, said nozzle being also provided with orifices in its base positioned vertically on each side of the nozzle center, supplying thereby auxiliary openings from the port 11 directly into the trap.

7. In a sanding device the combination of; a trap having a vertical inlet adapted for 10 the passage of sand through it into the trap, the latter also having an air intake port 11 and a discharge port 15 positioned laterally in alignment in opposing walls of the trap, below its inlet, a first pipe extending 15 from a source of air supply under pressure to a connection for discharge through the port 11, a control valve in said pipe, a nozzle having its base secured in the port 11, its

free end being approximately at the entrance of the port 15 within the trap, said 20 nozzle being also provided with orifices in its base positioned vertically on each side of the nozzle center, supplying thereby auxiliary openings from the port 11 directly into the trap, a second pipe extending from a 25 source of sand supply to a connection for discharge through the trap inlet, a third pipe extending from a receiving connection in the port 15 to a place of sand discharge, and a duplicate series of elements of the 30 kind described, extending from the control valve in the first pipe, through the trap and to a place of sand discharge opposed to that first mentioned.

THOMAS S. GILMORE.
